UNITED STATES PATENT OFFICE

143,168

DESIGN FOR A COMBINED JACK AND BRACKET MOUNTING

Harvey W. Rockwell, Cedar Rapids, Iowa, assignor to La Plant-Choate Manufacturing Co., Inc., Cedar Rapids, Iowa, a corporation of Delaware

Application March 10, 1945, Serial No. 118,392

Term of patent 7 years

(Cl. D41—1)

To all whom it may concern:

Be it known that I, Harvey W. Rockwell, a citizen of the United States, residing at Cedar Rapids, in the county of Linn and State of Iowa, have invented a new, original, and ornamental Design for a Combined Jack and Bracket Mounting, of which the following is a specification, reference being had to the accompanying drawings, forming a part thereof.

Figure 1 is a perspective view showing the front

and side of a combined jack and bracket mounting embodying my new design, and

Fig. 2 is a similar perspective view showing the rear and side of a combined jack and bracket mounting embodying said design.

I claim:

The ornamental design for a combined jack and bracket mounting, substantially as shown.

HARVEY W. ROCKWELL.
